UNITED STATES PATENT OFFICE.

SIMON COOPER, OF BROOKLYN, NEW YORK, ASSIGNOR TO IDEAL WRAPPING MACHINE COMPANY, A CORPORATION OF NEW YORK.

WRAPPING MACHINE.

Application filed May 14, 1920. Serial No. 381,453.

To all whom it may concern:

Be it known that I, SIMON COOPER, a citizen of the United States, and a resident of the city of Brooklyn, in the county of Kings and State of New York, have invented certain new and useful Improvements in Wrapping Machines; and I do hereby declare that the following is a full, clear, and exact description of the same, reference being had 10 to the accompanying drawings, and to the numerals of reference marked thereon, which form a part of this specification.

This invention relates to wrapping machines and though not restricted to such use 15 is particularly adapted for use in wrapping stick candy.

One of the objects of this invention is to provide means for wrapping a piece of paper around a stick of candy.

20 Another object of the invention is to provide means for twisting the ends of the paper after it has been rolled around the candy.

Other and further important objects of 25 this invention will be apparent from the disclosures in the specification and drawings.

The invention (in a preferred form) is illustrated in the drawings and hereinafter more fully described.

30 On the drawings:

Figure 1 is an end view of a machine embodying the present improvements.

Figure 2 is a plan view of the same.

Figure 3 is a plan view with part of the 35 upper structure removed.

Figure 4 is a detail view taken on the line 4—4 of Figure 2.

Figure 5 is a section on the line 5—5 of Figure 2.

40 Figure 6 is a section on the line 6—6 of Figure 2, with parts removed.

Figure 7 is a section on the line 7—7 of Figure 2.

45 Figure 8 is a section on the line 8—8 of Figure 2.

Figure 9 is a similar section to Figure 8, showing the parts in another position.

Figure 10 is a section on the line 10—10 of Figure 2.

50 Figure 11 is a section on the line 11—11 of Figure 7.

Figure 12 is a section on the line 12—12 of Figure 7.

Figure 13 is a section on the line 13—13 of Figure 6, with parts removed. 55

Figure 14 is a section on line 14—14 of Figure 10.

Figure 15 is a section on line 15—15 of Figure 14.

Figure 16 is a section on line 16—16 of 60 Figure 5, with parts removed.

Figure 17 is a view on an enlarged scale of one of the parts shown in Figure 8.

Figure 18 is a section on line 18—18 of Figure 2, with parts removed. 65

Figure 19 is a view taken on the line 19—19 of Figure 2.

Figure 20 is a view taken on line 20—20 of Figure 2.

Figure 21 is a view taken on line 21—21 of 70 Figure 2.

Figure 22 is a view taken on line 22—22 of Figure 21.

Figure 23 is a view taken on line 23—23 of 75 Figure 10.

Figure 24 is a vertical section through one of the twisting members.

Figure 25 is a plan view of the end portion of one of the twisting members.

Figure 26 illustrates the first step in the 80 wrapping of the candy.

Figure 27 illustrates the second step in the wrapping process.

Figure 28 illustrates the final step of the 85 process.

Figure 29 is a detail view of one part of the mechanism shown in Figure 21.

As shown in the drawings:

The sticks of candy 139 are fed into the machine along a chute 1 while a strip of 90 paper 138 is fed diagonally into the machine from a roll of paper 2. The paper is cut off

into proper lengths by a knife 3 so that when a stick of candy is rolled therein the paper will project beyond the ends of the 95 stick sufficiently to allow it to be twisted therearound.

One edge of the paper is wetted so that it will adhere to the stick of candy as the latter is pushed over it. The candy is then rotated between three rolls 4, 100 5 and 6, which wind the paper around the stick. Towards the end of the rotating

- operation the projecting ends of the paper are seized by twisting clamps 7, so that further rotation twists the ends of the paper. The wrapping operation is then complete 5 and the wrapped stick is discharged from the rolls onto a belt conveyor 8. The various steps in the wrapping process are illustrated diagrammatically in Figures 26, 27 and 28.
- 10 The machine is mounted on a platform 9 carried by a pedestal 10. For driving the mechanism a shaft 26 is provided having a pulley 27 thereon for connection to a suitable motor or other source of power. Connected to this shaft by gears 28 and 29 is a 15 cam shaft 30. The paper feeding mechanism is driven from the shaft 30. For supporting the roll of paper 2 and the mechanism connected therewith frame members 11 20 are obliquely attached to the platform 9.
- Depending from the members 11 are a pair of arms 12 (Figure 1) between which is journalled a reel 13 carrying the roll of paper 2. Pivotal secured to the lower 25 ends of the arms 12 are a pair of members 14 carrying a paper tension roller 15. To the lower outer end of the arms 14 is attached an arm 16 adapted to bear against the periphery of the roll 2 and limit the 30 downward movement of the tension roller 15. The paper in its passage from the roll 2 to the tension roller 15 passes over a guide roller 164 mounted on a bracket 17 attached to the arms 12. The paper, after it leaves 35 the tension roller 15, passes around a guide roller 18 (Figure 20) and from thence between a pair of feed rollers 19 and 20. Both of these rollers are grooved as at 21 and 22 for the reception of fingers 23 and 24, which 40 serve to act as strippers for preventing the paper strip winding itself up on either of the rollers 19 or 20, as well as guides in the introduction of the paper into the main part of the machine. Water is applied to the 45 left-hand edge of the roller 20 (Figure 21) from a container 230 pivotally attached to the frame members 11 at 240. In the bottom of the container is a slot through which the edge of a disc 25 extends for engagement 50 with the left-hand edge of the roller 20. Sufficient space is left between the slot and the disc 25 to keep the edge of the disc wet without allowing water to run through in a steady stream. As the container is pivoted at 240 the disc 25 rests on and is, therefore, always in contact with the roller 20. The disc 25 is driven from the roller 20 by 55 gears 33 and 34 by the intermediary shaft 35.
- 60 For keeping the periphery of the disc 25 clean and removing any paraffin, lint or the like picked up from the paper by the roll 20 and thereby transferred to the disc 25, a scraper 140 is provided. This scraper is 65 provided with a threaded stem 141 for en-

gagement with a knurled nut 142 rotatably mounted in a bracket 143 secured to one wall of the water container 230.

The roller 19 is provided with a hub 36 (Figure 21) journalled on a shaft 37. To 70 the outer end of the shaft 37 is secured an annular member 38 having spring pressed pins 39 mounted therein for engagement with the end of the hub 36, which is provided with ratchet teeth 40, as shown in Figure 75 29. With this construction if the shaft 37 is oscillated to and fro the hub 36 and the roller 19 mounted thereon is turned intermittently in one direction only.

The shaft 37 is oscillated by means of a 80 cam 41 on the shaft 30, which is provided with a cam groove 42, in which rides a roller 43 (Figure 18) on an arm 44. This arm is rotatably mounted on a stub shaft 45 and is connected by a link 46 to another arm 47 85 pivotally mounted on a stub shaft 48 parallel to the shaft 45. On the end of this second arm 47 is arranged a toothed segment 49, which meshes with a bevel pinion 50 on the end of the shaft 37 (Figure 21). Consequently as the cam shaft 30 rotates the toothed segment 49 oscillates to and fro and rotates the roller 19 every other stroke.

The paper is fed forward into the machine between the block 51 and the plate 52 therebeneath (Figure 8). When a sufficient length for wrapping one stick of candy has been fed into the machine it is cut off by means of the knife 3. This knife is pivotally mounted on the machine at 54 100 and is provided with an upstanding arm 55 connected by a link 56 to the lower end of a double rocker arm 57 secured to a shaft 100 the upper end of the arm carrying a roller 58, which runs in a cam groove 59 105 of a cam 60.

Preferably the rollers 19 and 20 and their operating mechanism are so arranged that one rotative movement thereof feeds into the machine sufficient paper for one stick 110 of candy. Conveniently, also, the cam which operates the knife is arranged to depress the latter immediately or shortly after the feeding operation has been completed.

The lower end of the chute 1, down which the sticks of candy are fed is downwardly inclined towards the upper surface of the block 51. A number of guards 61 are provided adjacent the lower end of the chute 1 (Figures 8, 9 and 17) adapted to retain the sticks in position on the latter. At their rear ends the guides are enlarged and slotted, as at 138^a, for engagement with a supporting bar 139 journalled at each end in the side members of the frame. Pivoted to the lower end of each guard is a latch 63 adapted when in the position shown in Figure 17 to prevent the passage of a stick of candy therebeneath. On the 125 130

forward side of this latch is a lug 64, to which a rod 65 is pivotally attached. This rod passes through a sleeve 66 pivotally mounted by pins 67 between projections 68 on the guard 61. A spring 69 is mounted on the rod 65 tending to move the rod 65 downwards and thereby move the latch rearwardly. Locknuts 70 and 71 are provided for limiting the movement of the rod 10 65 downwards.

In the block 51 a passage 72 is formed for a pusher-bar 73 to reciprocate therein (Figures 8 and 9). This pusher-bar is adapted to force a stick of candy against 15 and under the latch 63, as indicated in Figure 8. This pusher-bar is connected by a link 74 to a rocker arm 75 mounted on a shaft 76. Also secured to this shaft 76 is an arm 77 (Figure 7) connected by a link 20 78 to a rocker 79 on a shaft 80. This rocker carries a roller which runs in a cam groove 81 in the cam 60 (Fig. 5).

The mechanism for operating the rolls 4, 5 and 6 will now be described. In Figure 14 are shown the gears which connect these rolls together. Six gears 82, 83, 84, 25 85, 86 and 87 are provided all of the same diameter and same size of tooth. The gear 82 is on the main driving shaft 26, which carries the roll 4, and the gears 83 and 87 on either side of it are mounted on shafts 88 and 89 journaled in the main frame of the machine. The gears 84 and 86 are secured to the shafts 90 and 91, which carry 30 the rolls 6 and 5 respectively. Gear 85 rotatably arranged on the shaft 92, connects the gears 84 and 86. The ends of the shafts 90, 91, 92 are journaled in castings 93 adapted to be rocked about the axis of 35 the shafts 90 and 91 alternatively. The space between the rolls 4, 5 and 6, when the parts are in the position shown in Figure 14, is just sufficient to receive a stick of candy so that the latter may be engaged 40 and rotated by all of the rolls 4, 5 and 6 simultaneously. In order, however, to bring the candy stick so that it may be so acted on by the rolls, the roll 5 must be lifted as shown in Figure 8 to allow the 45 stick to pass thereunder. The roll 5 is then lowered for the wrapping and twisting operation. When those steps are complete the roll 6 is lifted to allow the stick to pass thereunder onto inclined rails 94 leading 50 to the belt conveyor 8. The alternate lifting of the rolls 5 and 6 is brought about by rocking the castings 93. For this purpose the latter are provided with lugs 96 and 97 pivotally connected to arms 98 and 99 on shafts 80 and 100. The shaft 80 is oscillated by a cam 102 (Figure 6) by means of an arm 103 having a roller 104 engaging a cam groove 105 therein. Similarly the shaft 100 is oscillated by a cam 60 65 60 (Figure 9) as previously described.

As the roll 5 is lifted the pusher bar 73 causes one of the candy sticks to pass thereunder, and it contacts with the moistened edge of the paper strip causing adhesion. The rotation of the rolls 4, 5 and 6 insures 70 that the candy bar is wrapped in the stick of paper, on account of the turning motion caused.

The paper strip is held tightly in position around the candy stick as the latter is brought into engagement with the rolls 4, 5 and 6 by a series of fingers 144 (Figures 7, 8 and 9). These fingers are secured to an arm 145 on a shaft 146, to which is attached an arm 147 connected by link 149 75 and lug 148 to the shaft 76 which operates the pusher-bar 73. Consequently as the pusher-bar propels a stick of candy into the space between the rolls 4, 5 and 6, the fingers 144 move in the opposite direction 80 until they contact with the opposite side of the candy stick, as shown in Figure 7. As the pusher-bar is retracted the fingers are also withdrawn into the position shown in 85 Figure 9 so that it will not interfere with the discharge of the wrapped stick.

The stick is further guided, held in position and finally ejected by a second set of fingers 150 secured to the shaft 92. These fingers are operated from the rock shaft 80 90 by means of arm 151, link 152 and arm 153.

The construction of the rolls 4, 5 and 6 is shown more particularly in Figure 23. Each roll consists of a shaft 110 having recessed portions 111 and intermediate projecting 100 portions 112. The latter are knurled to provide adequate gripping surface for the rings 113 of rubber mounted thereon. Clutch projections 114 are provided for connecting each roll to its corresponding shaft 26, 90 105 and 91. The recessed portions of the rolls are adapted to receive the projecting portions of the guards 61, latch 63 and the parts co-operating therewith, as the pusher bars 73, fingers 144 and ejectors 150.

Since the sticks of candy may vary in diameter or have excrescences thereon, it is desirable that a greater range of adjustment be provided than is afforded by the resiliency of the rubber rings 113. Preferably, therefore, one of the rolls, as 4, is carried by spherical bearings 154 at the ends of arms 155 secured to the rock-shaft 156 (Fig. 12). On this shaft are oppositely arranged lugs 157 and 158, in which are arranged set-screws 159 and springs 160 respectively, which bear against the underside of the plate 51 (Fig. 9). The set screws limit the upward movement of the roller 4, while the springs 160 allow the roller to yield resiliently under downward pressure.

In order to allow for the yield and bodily movements of the roll 4, it is connected to its driving shaft 26 by a flexible coupling or the like which in the present instance consists of 120

5 a clutch member 165 (Figure 12) having a
slidable tongue and mortise connection with
the end of shaft 26 and a cooperating clutch
member 166 secured to the end of the shaft
of roll 4 and having a slidable tongue and
mortise connection with clutch member 165
at substantially right angles to the first men-
tioned tongue and mortise connection, as
10 shown in dotted lines, providing thereby a
form of gimbal joint which flexes at
right angles to its axis.

15 The twisting mechanism is shown more
particularly in Figures 24 and 25. A sleeve
115 is mounted in the frame on each side of
the rolls 4, 5 and 6 with its axis in line with
the axis of the candy stick when it is being
20 rotated by all of the rolls 4, 5 and 6. To the
end of this sleeve a bracket 116 is attached
having pivoted thereto by pins 117 clamp-
ing plates 7. On the inner ends of the plates
25 are formed teeth 118 adapted to mesh with
rack teeth in a block 119 secured to the end
of a rod 120 slidably mounted within the
sleeve 115. With this arrangement by re-
ciprocating the rod 120 the plates 7 may be
30 brought towards and away from each other.
A spring 121 is provided for retracting the
block 119 and rod 120 to bring the plates
into clamping position, as shown in Figure
35 24. Separation of the plates is brought
about by rockers 122 pivotally mounted on
brackets 123 and carrying rollers 124 at their
upper ends for engagement with cam
grooves 125 in the peripheries of the cams
40 60 and 102.

45 After the twisting operation is complete
the wrapped sticks are discharged onto the
conveyer belt 8. This belt is carried by pul-
leys 126 (Figure 8) and 127 (Figure 2)
40 mounted on shafts 128 and 129 journaled in
the side members 130 and 131 of the frame
of the machine. The shaft 129 is rotated in-
termittently by means of a pawl 132 engag-
ing the teeth of a ratchet wheel 133 secured
45 to the end of the shaft 129. The pawl 132 is
pivotally mounted at 134 on a rocker 135
rotatably mounted on the end of the shaft
129. To the lower end of this rocker is con-
nected a link 136 attached to an arm 137 on
50 the shaft 80 oscillated by the cam 102.

55 I am aware that numerous details of con-
struction may be varied through a wide
range without departing from the prin-
ciples of this invention, and I therefore do not
purpose limiting the patent granted other-
wise than necessitated by the prior art.

57 I claim as my invention:

60 1. The method of wrapping cylindrical
articles comprising passing a strip of wrap-
ping material obliquely across the path of
movement of such article, cutting the strip
parallel to such path of movement, rotat-
ing the object to wrap the strip therearound,
65 and whilst the object is still rotating grip-
ping the ends of the wrapping material to

cause the latter to be twisted around the
ends of the object.

2. The method of wrapping sticks of
candy comprising wetting one edge of a
70 strip of wrapping material, passing such
strip obliquely across the path of movement
of such stick, cutting the strip parallel to
such path of movement, rotating the stick
75 to wrap the strip therearound and whilst
the stick is still rotating gripping the ends
of the strip to cause the latter to twist
around the ends of the stick.

3. A device of the kind described com-
prising three rollers, gears connecting each
80 of the rollers with the other two rollers,
means for driving one roller and means for
rocking the other two rollers alternatively
about the axis of first one and then the other
85 roller of such pair to allow first admittance
and then discharge of an article to be oper-
ated on by all three rollers simultaneously.

4. A device of the kind described com-
prising three rollers, gears connecting each
90 of the rollers with the other two rollers,
a driving shaft, a flexible connection be-
tween said shaft and one of the rollers, re-
siliently mounted supporting bearings for
the latter roller, and means for rocking the
95 other two rollers alternatively about the
axis of first one and then the other to allow
first admittance and then discharge of an
object to be operated on by all three rollers
simultaneously.

5. A device of the kind described com-
prising three rollers, gears connecting each
100 of the rollers with the other two rollers,
means for driving one roller, means for
rocking the other two rollers alternatively
about the axis of first one and then the other
105 roller of such pair, means for introducing a
cylindrical object and a piece of wrapping
material within the last mentioned rollers
in one position, and means for discharging
the wrapped article in the other position.

6. A device of the kind described com-
prising three rollers, gears connecting all
110 three rollers, a driving shaft, a flexible con-
nection between said shaft and one of the
rollers, resiliently mounted supporting bear-
ings for the latter roller, and means for
rocking one of the other rollers about the
115 axis of the remaining roller.

7. A device of the kind described com-
prising three rollers, means for driving one
120 roller, and means for rocking the other two
rollers alternatively about the axis of first
one and then the other roller of such pair
to allow first admittance and then discharge
of an object to be operated on by all three
125 rollers simultaneously.

8. A device of the kind described com-
prising three rollers, gears connecting each
130 of the rollers with the other two rollers,
means for driving one roller, a frame hav-
ing bearings thereon for the other two roll-

- ers, a shaft parallel to the rollers, cams thereon, and operative connections between the cams and the frame adapted to rock the frame alternately about the axes of the rollers journalled therein.
9. A device of the kind described comprising three rollers, gears on each roller, intermediate gears between each pair of first mentioned gears, means for driving one roller, and means for rocking the other two rollers alternately about the axis of first one and then the other roller of such pair to first admit and then discharge an object to be operated on by all three rolls simultaneously.
10. A device of the kind described comprising three rollers, gears connecting each of the rollers with the other two rollers, means for driving one roller, means for rocking the other two rollers alternately about the axis of first one and then the other roller of the pair to first admit and then discharge an object to be operated on by all three rollers simultaneously, a pusher for moving an article into position to be operated on by the rollers and an ejector adapted to discharge the article.
11. A device of the kind described comprising three rollers, means for driving one roller, means for rocking one roller about the axis of another roller towards and away from the third roller, and a pusher-bar adapted to project an article into engagement with the rolls when the rollers are in separated position, one of the rollers having an annular groove therein for the reception of the pusher-bar.
12. A device of the kind described comprising three rollers, means for driving one roller, means for rocking one roller about the axis of another roller towards and away from the third roller, a pusher-bar for projecting an article between one pair of rolls, and an ejector adapted to operate between another pair of rolls to discharge the article.
13. A device of the kind described comprising three rollers, means for driving one roller, means for rocking one roller about the axis of another roller towards and away from the third roller, a pusher-bar for projecting an article between one pair of rolls, and an ejector adapted to operate between another pair of rolls to discharge the article, the rolls being grooved annularly to provide space for the operation of the pusher-bar and ejector.
14. A device of the kind described comprising three rollers, means for driving one roller, means for rocking one roller about the axis of another roller towards and away from the third roller, a pusher-bar adapted to project an article into engagement with the rolls when the rollers are in separated position, and a supporting member adapted to engage the opposite side of the article to the pusher when such article is in position to be operated upon.
15. A device of the kind described comprising three rollers, means for driving one roller, means for rocking one roller about the axis of another roller towards and away from the third roller, a push-bar for projecting an article between one pair of rolls, a supporting member adapted to operate between another pair of rolls, and an ejector adapted to operate between the third pair of rolls.
16. A device of the kind described comprising a frame, rollers carried thereby adapted to rotate an article within a sheet of wrapping material, pairs of gripping jaws pivotally mounted on the frame, operating rods for said jaws having gear connections with the latter, and means for reciprocating said rods to cause the jaws to grip the projecting ends of the sheet of wrapping material whilst the article is being rotated to cause the wrapping material to be twisted around the ends of the article.
17. A device of the kind described comprising a pair of feed rolls, corresponding grooves in said rolls, and feed means and ejecting means arranged to project within said grooves.
18. A device of the kind described comprising a pair of feed rolls, both of said rolls having a series of annular grooves disposed therealong, and two series of stripping fingers arranged to project within said grooves and adapted to act as guides for a strip of material passed between the rolls.
19. A device of the kind described comprising means for wetting one edge of a strip of wrapping material as it passes into the machine, a chute for sticks of candy, means for passing the wetted wrapping material obliquely under the discharge end of the chute, means for cutting the wrapping material parallel to the chute, means for discharging the sticks one by one from the chute, means for rolling the stick within the cut-off portion of the wrapping material, and means for twisting the ends of the wrapping material around the ends of the stick.
20. A device of the kind described comprising means for wetting one edge of a strip of wrapping material as it passes into the machine, a chute for sticks of candy, means for passing the wetted wrapping material obliquely under the discharge end of the chute, means for cutting the wrapping material parallel to the chute, three rollers, gears connecting each of the rollers with the other two rollers, means for driving one roller, means for rocking the other two rollers alternately about the axis of first one and then the other roller of such pair, means for moving a stick from the bottom of the

chute together with the cut-off portion of wrapping material under one of the last mentioned rollers when rocked away from the first roller, and means for discharging 5 the wrapped stick under the other of the last mentioned rollers when rocked away from the first roller.

21. In a candy wrapping machine, a plurality of rolling elements defining a way 10 therebetween for receiving a stick of candy, means for obliquely feeding a strip of paper to said rolls, means for shearing said strip,

means for rotating said rolls for wrapping said sheared strip of paper on said stick, and gripping elements for seizing the ends 15 of the strip while acted upon by said rolls for twisting the same.

In testimony whereof I have hereunto subscribed my name in the presence of two subscribing witnesses.

SIMON COOPER.
